UNITED STATES PATENT OFFICE

156,853

PLATE OR SIMILAR ARTICLE

Lloyd I. Tucker, Glendale, Calif., assignor to Santa Anita Potteries, Los Angeles, Calif., a corporation of California

Application April 5, 1947, Serial No. 138,175

Term of patent 14 years

(Cl. D44—15)

To all whom it may concern:

Be it known that I, Lloyd I. Tucker, a citizen of the United States, residing in Glendale, county of Los Angeles, State of California, have invented a new, original, and ornamental Design for a Plate or Similar Article, of which the following is a specification, reference being had to the accompanying drawing, forming a part thereof, in which:

Fig. 1 is a plan view of a plate or similar article embodying my new design.

Fig. 2 is a transverse section taken on line 2—2 of Fig. 1.

I claim:

The ornamental design for a plate or similar article, as shown.

LLOYD I. TUCKER.
